UNITED STATES PATENT OFFICE.

JOSEPH REGINALD MONTAGUE STANFIELD, OF CARDIFF, WALES.

MAGNETO-STARTER.

1,386,081.

Specification of Letters Patent.

Patented Aug. 2, 1921.

Application filed November 23, 1920. Serial No. 426,077.

To all whom it may concern:

Be it known that I, JOSEPH REGINALD MONTAGUE STANFIELD, subject of the King of England, residing at East Canal Wharf, 5 Cardiff, Wales, Great Britain, have invented certain new and useful Improvements in Magneto-Starters, of which the following is a specification.

This invention is for improvements in or 10 relating to magneto-starters of the type wherein a driving-member is connected to the driven-member, which may be the magneto-armature shaft, through the medium of a spring, and a pawl is provided to hold 15 back the driven-member while the spring is loaded by turning the driving-member, which pawl is afterward automatically tripped so that the driven-member suddenly advances under the action of the spring and 20 thus a quick turn is given to the magneto-armature and the requisite spark is produced.

Magneto-starters of this type are usually 25 provided with some means for yieldingly locking the driving and driven members together when in the position for normal driving, and one object of the present invention is to provide such a yielding locking-device which shall be subject to less wear than those 30 at present on the market and which shall be of such construction that the cost of production may be decreased.

According to the present invention, a 35 magneto-starter of the type described, is characterized by the means for yieldingly locking the driving and driven members together when in the position for normal driving, comprising a portion of spring which moves with one member (that is the driving 40 or driven member) and a pin which moves with the other member, the said spring portion being so shaped that it provides a butting face for this pin sufficient to effect the requisite locking but not sufficient to prevent 45 the locking from being forced for starting purposes and being further so positioned that for starting purposes it is displaced by the pin in an approximately radial direction relatively to the axis of rotation of the mem- 50 bers, the resilience of the spring tending always to keep the said butting portion in the engaging position relatively to the pin.

The invention further relates to the specific construction of parts hereinafter fully 55 described whose shape is such owing to the

aforesaid form of locking-device that they can all be produced in quantity at a low price.

In the accompanying drawings which illustrate those parts of the magneto-starter 60 which are necessary to the understanding of the invention:

Figure 1 is a central section through the said parts along the axis of rotation of the driven member;

Fig. 2 is a section through the same parts on the line 2—2 of Fig. 1, and

Fig. 3 is a section through the same position of a modified form of the device.

The same letters indicate the same parts 70 throughout the drawings.

The spindle of the magneto is indicated at A and mounted on this is a disk-like member B which is secured by its boss B¹ to the cone-shaped end of the spindle and locked in 75 place by a nut B². Mounted on the boss B¹ is a dished member C whose central portion C¹ is surrounded by a spring D one end of which is fixed to the said central portion at D¹. The disk B carries a pin B³ which 80 projects into the dished member C and is engaged with the upper end of the spring D. The dished member C also carries a pin C² which lies in the path of the pin B³ and the spring D has on its outer end a projection 85 D² which butts against the opposite side of the pin C² to that on which the pin B³ is situated. The part of the spring which carries the projection D² tends to move outward and is in fact thrust inward by the pin C² 90 so that the butting portion D² is always kept against the pin C² when the parts are in the position shown in Fig. 2. In the edge of the disk B, notches E⁴ are provided and a pawl E pivoted at E¹ to a fixed part of the 95 mechanism not shown in the drawings is so placed as to engage either of the notches when brought to register with it. Projecting laterally from the pawl E is a pin E² and on the outer periphery of the dished 100 member C are two cams C³ while lie in the path of the pin E².

The operation of this device is as follows:

As the engine is cranked around, the member C is advanced in the direction of the arrow, Fig. 2, but the member B and therefore the magneto-shaft A is held against rotation by the pawl E. When the member C has been turned through an angle of 90° 110

from the position shown in the drawing, one of the cams C^3 comes into contact with the pin E^2 and thrusts the pawl out of engagement. The spring D has been loaded by the 5 advance of the member C , and consequently the member B will advance rapidly under the action of the spring until the pin B^3 strikes against the pin C^2 . This rapid advance movement of the member B gives the 10 requisite partial rotation to the armature spindle A to produce the necessary spark. Means not shown in the drawing are provided for throwing the pawl E out of action as soon as the engine is started, and the two 15 parts B and C are then yieldingly locked together for normal driving by the end of the spring D , which engages one side of the pin B^3 as shown in the drawing and which, by means of the projection D^2 , engages the opposite side of the pin C^2 . The projection D^2 is of a yielding character as will be readily understood, so that it does not interfere 20 with the movement of the pin C^2 away from the pin B^3 for starting purposes as it is then forcibly thrust aside, but it holds the pin C^2 against the pin B^3 with sufficient firmness for normal driving. The projection D^2 has a further use, namely that it decreases the 25 impact of the pin B^3 against the pin C^2 when the member B is tripped.

In Fig. 3, the parts B and C with their driving spring and yielding lock are the same as those shown in Figs. 1 and 2, but a further lock is provided by means of a separate piece of spring F which is secured in the dished member C and has an inwardly-directed butting projection F^1 . This projection co-operates with a pin G on the member B so that a dual lock is provided. Obviously the spring F with its projection F^1 could be arranged on the member C to co-operate with the pin B^3 instead of a separate pin G provided the end of the spring D is so arranged on the pin B^3 as not to be 35 displaced by the operation of the projection F^1 and the pin C^2 be so shaped as not to foul the spring F^1 . With this dual lock, the operation is the same as has been described with the single lock, that is, the projections D^2 and F^1 are forced when the member C is moved in the direction of the arrow for starting, and when tripping takes 40 place, the projections both act to cushion the part B .

It will be seen that in this apparatus, the parts are all readily constructed as there is no special shaping required in the dished member C which can be machined out in one operation, or can be stamped; the cams C^3 thereon can be formed by bulging out the 45 sides if stamping is the process employed. The member B also is a plain disk and has no parts subject to any particular wear so that it can be made in mild steel, with the result

that a magneto-starter of few parts requiring little machining is produced.

What I claim as my invention and desire to secure by Letters Patent is:—

1. In yielding locking means for the driving and driven members of a magneto-starter the combination with one of the aforesaid movable members of a portion of spring which moves with said member, and a pin which moves with the other member, the said spring portion being so shaped that it provides a butting face for the pin sufficient to effect the required locking of the one member relatively to the other but not sufficient to prevent such locking from being forced for starting purposes and said spring portion further being so positioned that for starting purposes it is displaced by the said pin in an approximately radial direction 70 relatively to the axis of rotation of the members, the resiliency of the spring tending always to keep the said butting portion in the engaging position relatively to the pin, substantially as set forth.

2. In yielding locking means for the driving and driven members of a magneto-starter the combination with one of said members, hereinafter called the first member, of a spring secured at one end thereto and having its other end curved to lie approximately along an arc struck from the 95 axis of rotation of said first member, the other end, hereinafter called the driving end, being engaged with a pin on the fellow member, hereinafter called the second member, and provided with a part which projects approximately radially outward from the axis of rotation of the members and between the aforesaid pin and the driving end of the spring to engage a second pin carried by the first member, said projecting portion 100 constituting a butting face for the pin on the second member sufficient to effect the required locking of the one member relatively to the other, but not sufficient to prevent such locking from being forced for 105 starting purposes, said projection being near enough to the pin on the second member so that the pin on the first member shall be held close against the pin on the second member when engaged by the butting portion, substantially as set forth.

3. In yielding locking means for the driving and driven members of a magneto-starter the combination with one of the aforesaid movable members of a portion of spring which moves with said member, and a pin which moves with the other member, the said spring portion being so shaped that it provides a butting face for the pin sufficient to effect the required locking of the one 120 member relatively to the other but not sufficient to prevent such locking from being forced for starting purposes and said spring

portion further being so positioned that for starting purposes it is displaced by the said pin in an approximately radial direction relatively to the axis of rotation of the members, the resiliency of the spring tending always to keep the said butting portion in the engaging position relatively to the pin,

one of the movable members being dished to receive the spring and coöperating pins, said dished portion further being closed in 10 by the coöperating member, substantially as set forth.

In testimony whereof I affix my signature.
JOSEPH REGINALD MONTAGUE STANFIELD.
